F. A. READ,

NEEDLE CARRIER FOR BUTTONHOLE MACHINES AND THE LIKE.
APPLICATION FILED JUNE 27, 1917.

1,286,410.

Patented Dec. 3, 1918.

UNITED STATES PATENT OFFICE.

FRED A. READ, OF LYNN, MASSACHUSETTS, ASSIGNOR TO REECE BUTTONHOLE MACHINE COMPANY, OF BOSTON, MASSACHUSETTS, A CORPORATION OF MAINE.

NEEDLE-CARRIER FOR BUTTONHOLE-MACHINES AND THE LIKE.

1,286,410.

Specification of Letters Patent.

Patented Dec. 3, 1918.

Application filed June 27, 1917. Serial No. 177,391.

To all whom it may concern:

Be it known that I, FRED A. READ, a citizen of the United States of America, and a resident of Lynn, in the county of Essex 5 and Commonwealth of Massachusetts, have invented certain new and useful Improvements in Needle-Carriers for Buttonhole-Machines and the like, of which the following is a specification.

10 This invention relates to sewing machines and particularly to the needle carrier thereof, the object of the invention being to provide a means whereby the needle may be adjusted bodily relatively to the axis of the 15 needle bar, thereby varying the depth of the stitch.

Another object of the invention is the provision of means on the needle carrier for creating a tension on the needle thread and 20 adapted to always retain its position relatively to said needle during the lateral adjustment of the latter.

The invention consists in certain novel features of construction and arrangement of 25 parts which will be fully understood by reference to the description of the drawings and to the claims hereinafter given.

For the purpose of illustrating the invention one preferred form thereof is illustrated 30 in the drawings, this form having been found to give satisfactory and reliable results, although it is to be understood that the various instrumentalities of which the invention consists can be variously arranged 35 and organized, and that the invention is not limited to the precise arrangement and organization of these instrumentalities as herein shown and described.

Of the drawings:

40 Figure 1 represents an elevation of a device embodying the principles of the present invention.

Fig. 2 represents an elevation of the same, looking at the left of Fig. 1.

45 Fig. 3 represents a horizontal section on line 3—3 of Fig. 2.

Fig. 4 represents a vertical section on line 4—4 on Fig. 1.

50 Fig. 5 represents an elevation of the needle bar, the upper end being shown in section, and

Fig. 6 represents an elevation of the needle carrier and needle removed from the needle bar.

Similar characters designate like parts 55 throughout the several figures of the drawings.

In the drawings, 10 is a needle bar preferably having a chamber 11 therein provided with a passage 12 extending from said chamber 11 to the periphery of said needle bar.

The lower end of the bar 10 is provided with a shank 13 and two lateral projections 14, 14 positioned above the upper end of said shank 13. The carrier block 15 has 60 mounted therein an eccentric 16 having an enlarged head 17 which bears against the lower face of said carrier block 15.

The eccentric 16 has a cylindrical opening 18 extending therethrough in which is positioned the shank 13. The carrier block 15 and the eccentric 16 are retained in position on the needle bar 10—13 by means of the head 19 of a screw 20 threaded to the lower end of the shank 13.

75 The block 15 is provided with an extension 21 projecting beyond the wall of the needle bar 10 with its upper end positioned between the projections 14 thereby preventing said block 15 from rotating about the 80 axis of the shank 13. In the extension 21 is positioned the needle 22 having a side groove 23 therein.

Upward movement of the needle 22 in the extension 21 is prevented by the block 24 85 in the needle receiving opening 25. This block 24 is secured in adjusted position relatively to said extension 21 by means of a clamping bolt 26, the shank of which extends through a slot 27 in said extension 21. 90

The needle 22 is prevented from being accidentally displaced from the opening 25 by means of the set screw 28.

Threaded to the block 15 is a lateral stud 29 having an enlarged head 30. The stud 95 29 extends through a plate 31 secured to the side of the needle carrier 15, said plate having a slot 32 therein adapted to receive a tongue 33 of a movable plate 34 through which said stud 29 extends.

100 The plate 31 is provided with a depression 35 into which extends a registering projec-

tion 36. Against the outer face of the plate 34 bears the washer 36* surrounding the stud 29, said washer being forced against said plate 34 by means of a spring 37 interposed between said washer and the head 30.

The plates 31-34 form a suitable tension device through which the supply of thread may pass from the discharge orifice 12 to the groove 23 in the needle 22 and thence 10 to the eye 38 in said needle.

The head 17 of the eccentric 16 is provided with a projection 39 by which said eccentric may be turned about the axis of the shank 13 when the clamping screw 15 19-20 has been loosened.

By turning the eccentric 16 about the axis of said shank 13 the needle 22 may be moved relatively to the axis of said shank and the depth of the stitch varied as 20 desired.

By mounting the tension device upon the needle block, the thread will always be in alinement with the groove 23 regardless of the position of the needle relatively to the 25 axis of the needle bar.

While in the drawings the needle 22 is shown parallel with the needle bar 10 it is true that said needle may be mounted in the block 15 at an inclination to the axis of said 30 bar and the position of said needle may be changed toward and from said shank 13 without changing its inclination.

It is believed that the operation and many 35 advantages of this invention will be fully understood from the foregoing description.

Having thus described my invention, I claim:

1. In combination with a longitudinally reciprocable needle bar, an adjusting eccentric surrounding a part of said bar and capable of being turned from without, means for securing said eccentric when adjusted, a needle carrier surrounding said eccentric, and inter-engaging projections 40 formed respectively on the bar and carrier for determining the circumferential position of the carrier.

2. In combination with a longitudinally reciprocable needle bar, an adjusting eccentric surrounding a part of said bar and capable of being turned from without, means for securing said eccentric when adjusted, a needle carrier surrounding said eccentric, and a radially arranged guide on 50 the bar and engaged by the carrier for determining the circumferential position of the carrier.

3. In combination with a longitudinally reciprocable needle bar, having a shoulder 60 substantially above its lower end, an adjusting eccentric surrounding a part of said bar in contact with said shoulder and capable of being turned from without, a needle carrier

surrounding said eccentric, and a securing screw at the bar lower end coöperating with 65 said shoulder for clamping said eccentric in adjusted position.

4. In combination with a longitudinally reciprocable needle bar, having a shoulder substantially above its lower end, an adjusting eccentric surrounding a part of said bar and capable of being turned from without, means for securing said eccentric when adjusted, a needle carrier surrounding said eccentric, a securing screw at the bar lower 70 end for clamping said eccentric in adjusted position, and a radially arranged guide on the bar and engaged by the carrier for determining the circumferential position of the carrier.

5. In combination with a longitudinally reciprocable needle bar having a shoulder substantially above its lower end, an adjusting eccentric surrounding a part of said bar, below said bar shoulder and having a 75 shoulder near its lower end, means for securing said eccentric when adjusted, a needle carrier surrounding said eccentric and confined between said two shoulders, and means for determining the circumferential position 80 of the carrier.

6. In combination with a longitudinally reciprocable needle bar, an adjusting eccentric surrounding a part of said bar, means for securing said eccentric when adjusted, 95 a needle carrier surrounding said eccentric and adapted to hold a needle in longitudinal position, means, such as 14, 21, on the bar and carrier for determining the circumferential position of the carrier, and a thread tension device located in suitable relation to the needle, and mounted on the needle carrier, whereby the operation of said eccentric will simultaneously and equally adjust both the needle and tension toward and from 100 the needle bar.

7. In combination with a longitudinally reciprocable needle bar, a needle carrier adapted to hold a grooved needle, a thread guiding tension device adapted to deliver 110 thread in line with the needle groove, and means for simultaneously and equally adjusting both said needle and tension transversely toward and from the needle bar.

8. In combination with a longitudinally reciprocable needle bar, a needle carrier device adapted to hold a needle longitudinally 115 to the bar, a thread tension device located in suitable relation to the needle, both said devices mounted on the needle bar, means 120 for adjusting the position of the tension device transversely of the needle bar, and means for securing the tension device in its adjusted position.

9. In combination, a needle bar; a needle block adapted to receive an eye pointed

grooved needle; a thread tension device composed of two plates one of which is pivotally connected to the other and carried by said needle block; means to hold said 5 plates normally in contacting position: a thread confining means formed by a projection from one plate entering a depression

in the other plate; means to adjust the said needle block laterally of the said needle bar; and means to lock said block in adjusted 10 position.

Signed by me at 4 Post Office Sq., Boston, Mass., this 15th day of June, 1917.

FRED A. READ.
